L. W. CHAPMAN.
FASTENER FOR SHIPPING CRATES.
APPLICATION FILED MAY 1, 1919.

1,331,696.

Patented Feb. 24, 1920.

Inventor.

L. W. Chapman

By *John Murphy Jr.*, Attorney.

UNITED STATES PATENT OFFICE.

LEMUEL W. CHAPMAN, OF INDIANAPOLIS, INDIANA, ASSIGNOR OF ONE-HALF TO
WILLIAM E. WACHTEL, OF INDIANAPOLIS, INDIANA.

FASTENER FOR SHIPPING-CRATES.

1,331,696.

Specification of Letters Patent.

Patented Feb. 24, 1920.

Application filed May 1, 1919. Serial No. 294,009.

To all whom it may concern:

Be it known that I, LEMUEL W. CHAPMAN, a citizen of the United States, residing at Indianapolis, in the county of Marion and State of Indiana, have invented certain new and useful Improvements in Fasteners for Shipping-Crates; and I do hereby declare the following to be a full, clear, and exact description of the invention, such as will enable others skilled in the art to which it app pertains to make and use the same.

This invention relates to new and useful improvements in fasteners for shipping crates of the collapsible or knock-down type and has for one of its objects the provision of means for detachably securing the sides and ends of the crate together and which will firmly hold the walls of the crate against movement in relation to each other.

Another object of this invention is the provision of means whereby the cover of the crate can be fastened in place when the sides and end walls are fastened together.

A further object of this invention is the provision of a fastener for shipping crates of the above stated character, which shall be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:—

Figure 1 is a transverse sectional view of a shipping crate illustrating the side and end walls thereof fastened together with my improved fastener.

Fig. 2 is a plan view of the fastener. Referring in detail to the drawing, I have elected to show only one end of a collapsible crate having my invention applied thereto and it will be understood that a similar fastener will be provided at the other end of the crate.

The numeral 1 indicates the end wall of the crate having abutting the edges thereof side walls 2. Positioned upon the ends and

side walls is a cover 3. A lever 4 is pivoted to the end wall 1 as illustrated at 5 and has connected thereto by pivots, rods 6. The rods 6 are disposed upon opposite sides of the pivot 5 and extend in opposite directions. The rods 6 have their ends bent to 60 form hooks 7. The free ends of the hooks 7 are bent rearwardly and extend parallel with the rods as illustrated at 8. The rods 6 are slidably supported by brackets 9 secured to the end wall 1 adjacent each edge 65 thereof and one bracket being disposed in a plane slightly above the other so as to correspond with the pivotal connections of the rods to the lever. The side walls 2 are provided with slots 10 which receive the hooks 70 7 and a portion of the rods 6 to permit the ends 8 to extend beyond the side walls during the movement of the lever 4 and as the lever 4 arrives in locking position, the rods 6 drop downwardly and the extension 8 75 passes into apertures 11 formed in the side walls and disposed slightly below the slots 10, thereby firmly locking the side walls to the end wall.

By swinging the lever 4 laterally on its 80 pivot the hooks 7 will be moved out of engagement with the apertures 11. When the hooks are in this position, the lever 4 is swung in a reverse direction or to a locking position again which retracts the hooks 85 causing them to pass through the slots 10 freeing the side walls from the end walls.

The cover 3 is provided with a slot 13 adapted to receive the upper end of the lever 4 when said lever is in a locking position, 90 and the upper end of the lever is provided with an opening 14 for the purpose of receiving a padlock or like fastener whereby the entire device is locked in assembled position.

While I have shown and described the preferred embodiment of my invention, it will be understood that minor changes in construction, combination, and arrangement of parts may be made without departing 100 from the spirit and scope of the invention as claimed.

Having thus described my invention, what I claim is:—

1. A fastener for crates including side 105 and end walls, a lever pivoted to the end wall, rods pivoted to said lever, and extending in opposite directions, hooks formed

on the ends of said rods, said side walls having slots to receive the hooks and a portion of the rod, said side walls having openings disposed in a plane below the slots to receive the ends of the hooks when the lever is swung into locking position.

2. A fastener for crates including side and end walls, a lever pivoted to the end wall, rods pivotally connected to said lever and extending in opposite directions and one rod being disposed in a plane above the other and on opposite sides of the pivot of the lever, hooks formed on the ends of said rods, brackets secured to the end wall and slidably supporting the rods, said side walls having slots and openings and said slots receiving the hooks and a portion of the rods and said openings adapted to receive the

ends of the hooks when the lever is swung into locking position.

3. A fastener for crates including side and end walls and a cover having a slot, a lever pivoted to the end walls, fastening means connected to said lever and adapted to secure the side walls to the end walls, said lever extending through the slot of the cover when in locking position and provided with an opening to receive an auxiliary fastening means.

In testimony whereof I affix my signature in presence of two witnesses.

LEMUEL W. CHAPMAN.
